STRAIGHT BAR KNITTING MACHINE

Harry Wilfred Start, Carlton, and Ernest Start, Wilford, England, assignors to George Blackburn and Sons Limited, Nottingham, England

Application April 25, 1938, Serial No. 204,162
In Great Britain December 5, 1936

3 Claims. (Cl. 66—98)

This invention relates to improvements in straight-bar knitting machines of the type known as "Cottons" in which facilities are provided for making complete full fashioned garments on one machine, thereby obviating the necessity for transferring the work from the needles of one machine to those of another machine and in order to obtain this result provision is made for setting back the middle portion of the combined 5 sinker sley and presser, so that knitting can be discontinued in a space in the middle of the needle bar, whilst knitting is continued on the needles outside that space. The presser in this type of knitting machine is formed by the front 10 edge of the lower sinker sley, and in order to set back the middle portion, a corresponding part of the sinker sley must be set back.

The drawback to the present arrangement is, that the effective length of the adjustable section 20 described cannot be varied, and as a result, there is no means of varying the width of the space in which the needles are put out of action, as is required to make hose with insteps of different widths, and the object of the present invention is 25 to provide the required adjustment for this purpose.

According to this invention, the adjustable sinker sley section, is comprised of a main middle portion and a series of short adjustable sections 30 which are disposed at each end of the middle portion, and any number of these short sley sections can be employed to vary the length of the adjustable sley and presser section, and consequently the width of the space in the middle of the needle 35 bar where the needles are put out of action, can be adjusted as is necessary to produce stocking feet with insteps of any requisite width.

The short adjustable sley sections described, 40 may each be equal in length to the space occupied by say two or more needles in the needle bar, and consequently the increase in the number of needles which is put out of action in the said bar by moving each short sley section back, is two or more needles, and any adjustment required is thus rendered possible.

The invention will now be more particularly described with reference to the accompanying drawing, in which—

Fig. 1 is a plan of a combined sinker sley and 50 presser constructed according to our invention.

Fig. 2 is an end elevation.

Fig. 3 a cross section taken on the line X X of 55 Fig. 1.

Fig. 4 a cross section taken on the line Y Y of Fig. 1, and

Fig. 5 a front elevation of the combined sinker sley and presser.

Fig. 6 is a plan of part of the sinker sley and presser showing the adjustable section moved back.

Like letters indicate like parts throughout the drawing.

In carrying out this invention, the fixed main part of the combined sinker sley and presser A, is formed with a recess in the middle of its length 10 to receive an adjustable section, and in the present arrangement this recess is filled in by a middle adjustable section B, and a series of short adjustable sections C disposed at each end of the middle section B. The short adjustable sections 15 C are of the same cross sectional shape as the adjustable middle section B, and all these adjustable sections are held down in the recess in the fixed main part A by means of two longitudinal bars D. These bars D extend from one end to the 20 other of the recess in the fixed main part A, and their ends are secured in recesses in the latter so that the upper faces of these bars D are level with the upper face of the fixed main part A, and the upper faces of the adjustable sections B and 25 C disposed in the recess in the said main part A.

These bars D are further disposed in recesses D¹ in the upper faces of the adjustable presser sections B and C, which are wide enough to permit of the latter being moved back the required 30 distance. The transverse tricks for the sinkers, are cut in the upper faces of the fixed part of the sinker sley A, and in the upper faces of both the longitudinal bars D and the adjustable sley sections B and C, as shown at K in Fig. 6, and the 35 tricks in the two longitudinal bars D form an effective support for the sinkers, and prevent the latter from working into the divisions between the adjustable parts B and C and the latter and the fixed main part.

The middle portion B of the adjustable section is adjusted and held in either of its two positions by the same means as previously used for this purpose, while the required number of the short adjustable sections C, which are introduced 45 between the ends of the middle part B and the ends of the recess in which the whole of them are located, are connected to the middle part B so that they can be adjusted with the latter, by the following arrangement.

On the underside of one end of the fixed part of the sinker sley A, is a slide E, and on the underside of the other end is a corresponding slide F. The outer end of the slide F is connected to and longitudinally adjusted by means of a screw 50 55

F¹, while the outer end of the other slide E is connected to and longitudinally adjusted by means of a screw E¹. Connected to the inner ends of each of these slides E and F are keys or splines which engage in grooves or keyways which are carried along the underside of all the adjustable sley and presser sections B and C, and these keys or splines are adapted to lock the short adjustable sections C to the middle adjustable section B or to the fixed main part of the sinker sley A as required.

The inner end of the slide F is for instance provided with a key or spline F² (see Fig. 3) which extends up through an opening in the 15 fixed main part A and engages in a groove or key-way which is carried along the underside of all the short adjustable members C at this end, and serves to lock them to the fixed main part A. Disposed in a groove in the middle adjustable 20 member B which registers with the grooves in the short members C, is a key or spline F³ (see Fig. 4) which is also connected to the slide F by a downwardly extending pin F⁴ which engages in a transverse slot F⁵ in the said slide F. When the 25 slide F is moved to the right, the key or spline F² will release the short sections C in succession, and those released by this key F² will be locked to the section B, by the key or spline F³ which moves with the key or spline F², and it thus 30 follows that the short sections C when released from the fixed main part A, will be locked to the adjustable middle portion B, and that the short sections C which are thus locked to the middle part B, can move back with the latter, owing to the pin F⁴ in connection with the key F³ engaging in a slot F⁵ in the slide F.

The slide E is in like manner provided with a key or spline E² and is connected to the other key or spline E³ in connection with the short adjustable sections C at the other end of the middle part B, by a pin E⁴ and a slot E⁵ in the slide E and it thus follows that when the slides E and F are moved outwards, the short adjustable sections C at each end of the middle portion B, will be released in succession from the fixed main part of the sinker sley A, and connected to the middle part B of the adjustable section, and the length of the adjustable section can thus be conveniently increased, and subsequently reduced again by reversing the operation.

The slides E and F may be provided with pointers H which are disposed in front of fixed scales J near the adjusting screws E¹ and F¹, and provide convenient means for adjusting the slides E and F in the required positions.

What we claim as our invention is:

1. In a straight-bar knitting machine, a combined sinker sley and presser consisting of a fixed part, an adjustable middle section that can be moved back, a series of short adjustable sections at each end of the adjustable middle section, sliding keys which are adapted to connect the short sections in each group to the fixed part, sliding keys for connecting the short sections in each group to the adjustable middle section and means for adjusting the two keys associated with each group of short sections simultaneously whereby the latter can be released from the fixed part and connected to the adjustable middle section and vice versa, substantially as described. 20

2. In a straight-bar knitting machine, a combined sinker sley and presser consisting of a fixed part, an adjustable middle section, a series of short adjustable sections at each end of the adjustable middle section, sliding keys for connecting each group of short sections to the fixed part, sliding keys for connecting each group of short sections to the adjustable middle section, a slide at each end of the fixed part to which the two keys in connection with the corresponding group of short sections are connected, and screws for adjusting these slides and the keys longitudinally whereby the short sections are in succession released from the fixed part and connected to the adjustable middle section when the slide is moved in one direction and this operation is reversed when the slide is moved in the reverse direction, substantially as described. 35

3. In a straight-bar knitting machine, a combined sinker sley and presser consisting of a fixed part, an adjustable middle section that can be moved back, a series of short adjustable sections at each end of the adjustable middle section and sliding keys in connection with each group of short sections which are adapted to connect the said sections to either the fixed part or the adjustable middle section as required, substantially as described. 40 45
